ABSORBENT SOLUTION FOR CORE OVEN FUMES

Raymond H. Harbin, Livonia, Mich., assignor to Ajem Laboratories, Inc., Livonia, Mich.

No Drawing. Filed Sept. 19, 1956, Ser. No. 610,711

3 Claims. (Cl. 252—192)

This invention relates to the treatment of fumes from foundry core ovens and, more particularly, to materials and formulations for removing from such fumes and the exhaust ducts through which they pass noxious, dangerous and harmful products contained therein.

In conventional foundry practice, sand molds and cores used for casting sometimes have binders or bonding agents added to the sand, or other agents applied over the surface of the mold or core, which are subsequently decomposed by baking or other treatment of the mold, etc. Such bonding agents include carbohydrates, such as flour, starch derivatives, sugars, especially molasses, oils, resins and other organic materials. Since such bonded sand is most often used in cores, we shall refer here to "core" as representative of the various articles which may be made of such bonded sand, including molds, patterns, etc.

As these cores are passed through a core oven, decomposition of the organic materials produce by-products many of which are volatile in nature or in such finely divided solid or fog form as to be carried away with the effluent fumes from the core oven; and these fumes also entrain fine solid particles of the core materials such as sand, resins, fillers etc., or dusts carried into the core ovens.

It has been found that many components of such core oven effluents are hazardous or create a legal nuisance. Volatile products in the stack may present a serious explosion and fire hazard. After they condense on the inside of an exhaust stack they build up masses of inflammable material, which increase the fire hazard. The removal of these has required expensive manual labor, and the chipping away of resinous and carbonaceous deposits has often resulted in damage to the apparatus being cleaned. The loss of operating time while apparatus is shut down for cleaning, and even more when it is shut down for repairs after damage by fire or by maintenance crews, can be a serious matter.

Additionally, such effluents may contain odiferous or irritating components which create unpleasant or even hazardous conditions for persons in the vicinity of the core oven exhaust, and even such of the components as are neither hazardous nor noxious may be of a corrosive character and thus may attack exhaust ducts or nearby valuable articles or structures. When deposits build up on the apparatus their removal from time to time may be very expensive, especially considering loss of production.

The amount of such materials produced in a large foundry operation is too great to merely wash out of the fumes and discharge to the sewer. It is important for such operations therefore to obtain a high efficiency in the use of wash liquids.

As more particularly set forth in the copending application of Orlan Arnold, Dewey Evans, Willard Johnson and Emil Umbrecht Serial No. 608,365 filed September 6, 1956, such effluent fumes from core ovens can be treated by washing to remove therefrom objectionable by-products and residues contained therein and the fumes

2

promptly chilled to avoid fire hazard before exhausting the fumes into the atmosphere or through exhaust stacks. If conditions are such that deposits can form on exhaust ducts, etc., from the oven or on the washing apparatus itself, they can be treated with a material which will remove them and wash them away.

This invention relates particularly to materials and formulations adapted for use in such washing to remove, solubilize, neutralize, and/or otherwise render unobjectionable the liquid, gaseous and/or solid materials encountered in fumes from core ovens and the like.

One object of this invention is to provide formulations and materials for making washing solutions for core oven fumes adapted to solubilize, neutralize, de-odorize and/or remove objectionable components therein.

Another object of this invention is to provide a washing composition of the character described adapted to treat various materials found in core oven fumes to prevent corrosion of the apparatus thereby and condensation 20 or build up of the materials on the apparatus.

A further object of this invention is to provide washing materials of the character described for treating core fumes and the like adapted to solubilize components in said fumes and/or to digest or disperse solid or insoluble 25 components therein for removal from the fumes and from the exhaust ducts in fluid solution or dispersion, so that they can be pumped and stored and flowed through pipes without clogging or expensive maintenance.

Still another object of this invention is to provide fluid 30 washing materials of the character described for use in treatment of core oven fumes and the like in washing apparatus of the character described and adapted to react with, neutralize, remove, solubilize, de-odorize, and/or otherwise render unobjectionable a wide variety of waste 35 products and by-products.

Other objects and advantages of this invention will be apparent from the following description and the appended claims.

One of the difficulties frequently encountered in attempts to render core oven fumes unobjectionable involves the fact that the exact identity of many of the products encountered is not known with certainty, nor are many of the reactions forming such products within the core oven determined in detail. The present invention is based in part on a study of these products, which indicates that the objectionable and hazardous products are fine soot and graphite, ash particles, corrosive acidic organic components, toxic and lacrymator components, and a variety of resinous and resin-forming components. 50 The composition of core oven fumes varies considerably as the baking progresses; and as the fumes pass through ducts from the ovens, various chemical reactions progress therein and various components originally in the fumes are condensed and deposited on the inner walls of the apparatus.

Many of these organic materials, formed in the oven include active unsaturated linkages and active monomer or low polymer groups such as aldehydes, acids, etc. Consequently, resinous materials are formed or further polymerized to hard resinous deposits on the inner walls of the exhaust ducts, and some of these materials become harder and more insoluble with the passage of time, resisting mechanical and solvent removal.

Heretofore, removal of materials from such gases has been generally regarded as a dust collection or gas scrubbing operation. According to the present invention it is properly treated as a problem of chemical reaction as well as of surface-active chemistry.

The washing materials embodying this invention include components providing a wide adaptability for treating, removing, and rendering unobjectionable these various components of core oven fumes. Such washing ma-

terials include components which neutralize corrosive materials in the fumes, prevent or interfere with deposition of organic residues on the apparatus, solubilize and remove such materials as may deposit on the interior of the exhaust ducts or the fume washing apparatus, deodorize the effluent fumes, convert fume components to a soluble or dispersable form for continuous removal, arrest or control undesired polymerization or chemical reaction among the constituents, prevent or control corrosion or erosion of the ducts and/or other equipment, and eliminate fire and explosion hazards from the exhaust ducts.

Washing materials embodying this invention include an alkaline and detergent component, a defoamant component, a corrosion inhibiting component, along with solvents, etc., and may also contain a deodorizing or odor masking component. Illustrative of various materials with which satisfactory results have been obtained in the treatment of core oven fumes with washing formulations embodying this invention, are the following:

Neutralizing and detergent component:

Sodium tripolyphosphate... Sodium carbonate.
Tetrasodium pyrophosphate... Sodium bicarbonate.
Borax... Sodium sesquicarbonate.
Sodium metasilicate... Sodium hydroxide.
Trisodium phosphate.

Defoamant component:

Polypropylene glycol... Polyglycol alkyl ethers.
Polyalkylene glycol polymers... Polyglycol aromatic ethers.
Silicone oil.

Corrosion inhibiting component:

Sodium or potassium dichromate and mixtures thereof.

Sodium or potassium nitrite and mixtures thereof.

Deodorant or odor masking component:

Geraniol ($C_9H_{15}CH_2OH$)... Butyl propionate.
Geraniol butyrate
($C_3H_7COOC_{10}H_{17}$)... Iso amyl valerate.
Geranyl acetate
($C_{10}H_{17}O_2C_2H_3$)... Iso amyl salicylate.

The polypropylene glycols and polyalkylene glycol polymers referred to above are preferred as the defoamant component because such materials appear to provide a proper balance between a water phase and organic phases in a washing operation of the character described. With polypropylene glycols a molecular weight range from 2000 to 4000 is preferred, although molecular weight ranges from 1000 to 10,000 may satisfactorily be used. The polyalkylene glycol components referred to are high polymers prepared from propylene and ethylene oxides to give a polyglycol type of molecule. Polyglycol alkyl ethers, and polyglycol aromatic ethers, such as polyglycol phenyl ethers have proven very effective as defoamants in washing core oven gases. Of the polyglycol alkyl ethers having a molecular weight in the range from 400 to 2000, polyglycol P-600X-octyl ether is preferred. Of the polyglycol aromatic ethers having a molecular weight in the range from 500 to 4000, polyglycol P-1000 phenyl ether is preferred.

As with the propylene glycol, the best materials are of no or little solubility in water, have a Saybolt viscosity in the range of 1700 seconds at 100° F. and 250 seconds at 210° F. although lower or higher viscosity materials may be used with appropriate adjustment of concentration or dilution. Also, a distinct organic solvent may or may not be required depending upon the solubility characteristics of the other components. In formulations where an aliphatic solvent is used it is selected to have an open-cup flashpoint of at least above 180° F. and preferably above 200° F.

Satisfactory results have been achieved using from 20% to 99.8% of a detergent component, which may itself perform the function of the alkaline buffer component or may include from 20% to 45% of a separate alkaline

buffer. With such components, from .05% to 5% of a corrosion inhibiting component are used and from .01% to 5% of a defoamant component, depending on the specific materials included, and the material to be cleaned.

Lastly and optionally the composition includes 0.05% to 0.5% of a deodorant or odor masking component.

Illustrative washing materials embodying this invention and utilizing an alkaline buffer component and a detergent component are noted within the following ranges of materials and proportions:

	Alkaline buffer component:	Percent
15	(Sodium carbonate, sodium bicarbonate and/or sesquicarbonate)	20 to 45
15	(Sodium tripolyphosphate, borax and/or tetrasodium pyrophosphate)	10 to 50
15	(Trisodium phosphate)	10 to 40
20	Defoamant component:	
20	(Polypropylene glycol)	0.1 to 5
20	(Silicone oil)	0.1 to 1
25	Corrosion inhibitor:	
25	(Sodium and/or potassium dichromate and/or sodium and/or potassium nitrite)	0.1 to 3
25	Aliphatic solvent	0.1 to 5

Satisfactory results have been obtained by adding a solid mix within the above ranges of proportions and materials to water in an amount to obtain a pH in the wash water within the ranges of approximately 7 to 10.5, although a pH range of about 7.2 to 8.5 is advantageous, tending to produce less foaming and more economical use of the active ingredients.

The following are illustrative of satisfactory formulations embodying this invention:

	Percent
35	Sodium metasilicate
35	Corrosion inhibitor
35	Polypropylene glycol

40 Satisfactory results are obtained with formulations having the above ranges of proportions and materials when the mix is added to the wash water to maintain a pH above about 8.5 while the washing system is in operation. If less of the sodium metasilicate is desired in the range of, for example, down to 50%, a separate neutralization component may be added as, for example, sodium hydroxide in the range of 0.1% to 50%, for the desired pH control, along with 0.05% to 5% of the corrosion inhibitors and polyalkylene glycol defoamants. Satisfactory results are also obtained with the phosphate types of detergent components without a carbonate or hydroxide component as, for example, in mixtures having sodium tripolyphosphate and/or tetrasodium pyrophosphate above about 75% mixed with additional amounts of trisodium phosphate and the foregoing amounts of corrosion inhibitor and defoamant components to give the desired pH. Sodium metasilicate and sodium tripolyphosphate may satisfactorily be intermixed as the detergent and alkaline buffer components, and satisfactory results are obtained with trisodium phosphate substituted for as much as 25% of sodium metasilicate in the above formulations. A deodorizing odor masking component may satisfactorily be added to the various foregoing formulations in amounts ranging from 0.05% to 5% thereof.

60 Two typical specific formulations illustrate of washing materials embodying this invention are as follows:

Formulation one:

70 32.6% soda ash
32.6% sodium tripolyphosphate crystalline
0.5% polypropylene glycol
32.6% trisodium phosphate crystalline
0.5% aliphatic solvent
0.1% silicone defoamant
1.0% sodium dichromate

Formulation two:

97% sodium metasilicate
 1% sodium dichromate
 2% polypropylene glycol, molecular weight 4000.

Accordingly, formulations and materials are provided for adding to the wash water used in washing the effluent fumes from foundry core ovens, and these materials digest, solubilize, react with, or neutralize various objectionable components in such fumes to remove the components into an aqueous suspension or sludge in the washing system or otherwise render them unobjectionable. Such suspension may then be run into a sewer or effluent stream or into a lagoon or sump etc. depending upon conditions and limitations on contamination.

In this specification I have shown and described a preferred embodiment of my invention and various modifications thereof; but it is to be understood that these are not intended to be exhaustive or limiting of the invention but, on the contrary, are given for purposes of illustration in order that others skilled in the art may fully understand the invention and the principles thereof and the manner of applying it in practical use so that they may modify and adapt it in various forms, each as may be best suited to the conditions of a particular use.

We claim:

1. A solution for treating and removing by product materials from foundry core oven fumes which consists of an aqueous solution having a pH range of about 7 to 10.5 of a composition consisting essentially of about 20% to 99.8% by weight of an alkaline dispersing and detergent component selected from the group consisting of sodium tripolyphosphate, tetrasodium pyrophosphate, borax, sodium metasilicate, trisodium phosphate, sodium carbonate, sodium bicarbonate, sodium sesquicarbonate, sodium hydroxide, and mixtures thereof; about 0.01% to 5% by weight of a liquid defoamant selected from the

group consisting of polypropylene glycol, polyalkylene glycol polymers, silicone oil, polyglycol alky ethers, polyglycol aromatic ethers, and mixtures thereof; and about 0.05% to 5% by weight of a corrosion-inhibiting component selected from the group consisting of the dichromates and nitrites of sodium and potassium and mixtures thereof.

5 2. A composition as recited in claim 1 in which the pH of said solution is within the range of about 7.2 to 8.5.

10 3. A composition as recited in claim 1 which also includes about 0.05% to 0.5% by weight of an odor masking material selected from the group consisting of geraniol, geraniol butyrate, geranyl acetate, butyl propionate, 15 iso amyl balsalate iso amyl salicilate, and mixtures thereof.
